UNITED STATES PATENT OFFICE.

NICHOLAS JENKINS, OF WATERBURY, CONNECTICUT, ASSIGNOR TO
HOLMES, BOOTH & HAYDENS, OF SAME PLACE.

DESIGN FOR A PENDANT FOR LAMPS, &c.

SPECIFICATION forming part of Design No. 16,350. dated October 27, 1885.

Application filed September 16, 1885. Serial No. 177,310. Term of patent 7 years.

To all whom it may concern:

Be it known that I, NICHOLAS JENKINS, a citizen of the United States, residing at Waterbury, in the county of New Haven and State of Connecticut, have invented a certain new and original Design for Pendants for Lamps, &c.; and I do hereby declare the following to be a full, clear, and exact description of the invention, such as will enable others skilled in the art to which it appertains to make and use the same.

Figure 1 is a view in side elevation of a lamp-shade supporter or ring ornamented in accordance with my design. Fig. 2 is an enlarged detail view of the ornamental pendant detached from the shade supporter or ring.

The leading feature of my design is the ornamental pendant B, which consists, essentially, of the rosette a, to which a spheroidal drop, c, may be loosely connected. The rosette may be provided with a suitable hook or other device, b, at one side for attaching the ornamental pendant to the lamp-shade supporter A, and a similar hook or a link, b', is

provided at the opposite side for connecting 25 the rosette and the spheroidal drop together. The rosette may be of any suitably ornamental outline or configuration, and the drop may be engraved upon its exterior or have any superficial ornamentation, either in relief or in taglio, as desired.

Several of the above described pendants are to be attached at intervals upon a shade-ring, A, as shown, or elsewhere.

What I claim is—

1. The design for a pendant, consisting of the rosette a and the spheroidal drop c, substantially as shown and described.
2. The design for a lamp-shade supporter or ring, substantially as herein shown and described, the same consisting of a supporting-ring having pendants B, as set forth.

In testimony whereof I affix my signature in presence of two witnesses.

NICHOLAS JENKINS.
